UNITED STATES PATENT OFFICE.

THOMAS R. GRIFFITH, OF WILKES-BARRÉ, PENNSYLVANIA.

CHUTE-LOADER.

SPECIFICATION forming part of Letters Patent No. 430,800, dated June 24, 1890.

Application filed March 26, 1890. Serial No. 345,417. (No model.)

To all whom it may concern:

Be it known that I, THOMAS R. GRIFFITH, a citizen of the United States, and a resident of Wilkes-Barré, county of Luzerne, and State 5 of Pennsylvania, have invented a certain new and useful Chute-Loader for Loading Coal and other Materials, of which the following is a specification.

The object of my invention is to provide a 10 device for preventing breakage of coal or other material loaded by falling from the storage pocket or bin into the car or other conveyance.

The invention will be best understood by 15 reference to the accompanying two sheets of drawings.

Figure 1 is a general side elevation showing the loader in connection with a coal-breaker. Fig. 2 is an enlarged side elevation 20 of front end of loader. Fig. 3 is a plan view of front end. Fig. 4 is a side elevation of back end of loader. Fig. 5 is a plan view of back end. Fig. 6 is a section on line A A. Fig. 7 is a section on line B B. Fig. 8 is a 25 pair of grooved sheaves upon which the loader rolls.

Letters of like name and kind refer to like parts in each of the figures.

In Fig. 1, *a a* are the pocket or bin stringers; *c*, the pocket or bin where coal or other material is stored to be loaded; *c''*, gate or outlet from pocket. *E E E* is the loader proper. The sides *e e* are of angle-iron and sheet metal riveted together, curved in the 30 manner shown and bending upward in the arc of a circle. A curved bottom *f* is provided, made of sheet metal, terminating at *f''*, which, when the loader is in the position shown by full lines in Fig. 1, (which is the 35 normal position to start loading,) is three or four inches back of the point of lip-chute *g*. The sides at the back end, Figs. 4 and 5, are coupled together by an iron strap *h*. Angle-plates *i i* (which are flanged to catch timbers 40 *j* and *j'*) are bolted between side plates *e e* and coupling-strap *h*. Connecting to the angle-plates *i i* is a rod *l*, to which is attached a chain *v* and weights *k k''*. On the front end, 45 Figs. 2 and 3, is riveted a hood *y*, made of sheet metal, forming a pocket to prevent overflow of material when loader is in position shown in full lines in Fig. 1, to which is at-

tached an operating-chain *o*, which is carried around sheaves to loading-platform *D*. The feed-gate *p* is made of sheet metal and connected to yoke *p''* by means of rods *p³*. Yoke *p''* is for the purpose of keeping the lifting strain on gate *p* the same at all points. A light chain *q* is attached to yoke *p''* and is carried over sheaves to loading-platform *D*. 55

The loader is supported by and rolls upon two or more pairs of cast-iron sheaves *m m'*, provided with grooves, into which the edge of side angle-irons *n* runs.

When loader is not in operation, its position 60 is as shown by dotted lines in Fig. 1. After car or other conveyance *d d* is in position coal or other material is allowed to come through gate *c''* and run over lip-screens through lip-chute *g* into loader. The weight *x* is then raised by lifting on chain *o*. The loader will then assume the position shown by full lines in Fig. 1, the weights *k k''* being insufficient to hold loader in position, as shown by dotted lines, without the weight *x*. The 65 clippings from lip-screen *S* fall into chute *A* or into the auxiliary chute *A'*. (Shown in Fig. 1.) The two streams thus formed meet at *A²*, and are discharged at *A³* into the conveyer *t⁰*. 70

During the operation of loading the loader will be gradually rolled back, *k''* coming to rest before this operation is completed, and when the car or conveyance is full will assume again the position shown by dotted lines in 75 Fig. 1.

The operation of rolling the loader back is done from loading-platform *D* by drawing on operating-chain *o*. The loading-gate *p* is also operated from loading-platform *D*, and is 80 opened and closed to feed material into car or conveyance by drawing and slackening the chain *q*.

The terminal point *f''* of bottom sheet *f*, when loader is rolled back, is at *r*, which will 85 not interfere with chute *A*, above described.

Having therefore described my invention, what I claim as new, and desire to protect by Letters Patent, is—

1. The combination of the bin having the 90 discharge-opening, the chute formed in an arc of a circle and placed beneath said discharge-opening, and the sheaves on which the chute rolls, substantially as described.

2. The combination of the bin which has a discharge-opening, the chute formed in the arc of a circle and placed beneath said opening, and the sheaves on which said chute rolls, together with chains attached to said chute leading over pulleys and attached to counter-weights, substantially as described.

3. The combination of the bin which has a discharge-opening, the chute formed in the arc of a circle and placed beneath said discharge-opening, the sheaves on which said chute is mounted, the feed-gate at the end of said chute, and the chain extending from said feed-gate to the operator's platform, substantially as described.

4. The combination of the bin which has a discharge-opening, the chute formed in the arc of a circle placed beneath said discharge-opening, the sheaves on which said chute is mounted, the feed-gate, the pivoted yoke, and the chain connected to said feed-gate and pivoted yoke and extending to the operator's platform, substantially as described.

5. The combination of the bin which has a discharge-opening, the chute formed in the arc of a circle placed beneath said discharge-opening, the sheaves on which said chute is mounted, the feed-gate, the pivoted yoke, and the chain connected to said feed-gate and pivoted yoke and extending to the operator's platform, together with the guide-sheave for

said chain mounted on the chute, substantially as described.

6. The combination of the bin which has a discharge-opening, the lip-screen arranged with reference to said discharge-opening, the adjustable chute into which the material passing over said screen is discharged and which has its bottom cut away in part, the stationary chute which conducts away the clippings from said lip-screen, and the sheaves on which the first-named adjustable chute is mounted, substantially as described.

7. The combination of the bin which has a discharge-opening, the lip-screen arranged with reference to said discharge-opening, the chute into which the material over said screen is discharged and which has its bottom cut away in part, the stationary chute which conducts away the clippings from said lip-screen, and the sheaves on which the first-named chute is mounted, together with the conveyer into which the lip-screenings are discharged, substantially as described.

In testimony that I claim the foregoing as my invention I have signed my name, in presence of two witnesses, this 24th day of March, 1890.

THOMAS R. GRIFFITH.
